UNITED STATES PATENT OFFICE

WILLIAM C. GROB, OF TOLEDO, OHIO

ABRADING MACHINE

Application filed February 23, 1926, Serial No. 89,939. Renewed September 26, 1932.

This invention relates to dressing or treating surfaces of stock.

This invention has utility when incorporated for grinding and buffing metallic strips, 5 as automobile bumpers.

Referring to the drawings:—

Fig. 1 is a side elevation of an embodiment of the invention in a machine for grinding rough metallic strip stock, and after plating 10 thereof, the buffing of such stock;

Fig. 2 is a plan view of the machine of Fig. 1;

Fig. 3 is an end view of the machine of Fig. 2 from the left;

15 Fig. 4 is a detail view of one of the abrading jacks and its carrier;

Fig. 5 is a detail view of a stock holding device for holding the material acted upon in position with its support during the abrad- 20 ing operation;

Fig. 6 is a perspective view of an automobile bumper strip, such as may be handled hereunder for continuous operation;

Fig. 7 is a wiring diagram of the control 25 for the installation hereunder;

Fig. 8 is a fragmentary view of an abrader automatic shifter device as controlled by the stock being treated or surfaced;

Fig. 9 is a section on the line IX—IX, Fig. 30 8, looking in the direction of the arrow;

Fig. 10 is a fragmentary view on the line X—X, Fig. 9, looking in the direction of the arrow;

Fig. 11 is a partial view of the control 35 device of Fig. 8, showing the travel of the device for shifting the abrading member away from active position as to the stock being treated;

Fig. 12 is a plan view of the device in the 40 position shown in Fig. 8;

Fig. 13 is a plan view of the device in trip or clearance position as controlled by stock moving therethrough to allow the abrading element to be retained in working position;

45 Fig. 14 is a plan view of the device in the tripped position as shown in Fig. 11; and

Fig. 15 is a fragmentary view of a portion of the conveyor belt showing the flights thereon.

50 Main frame 1 is shown as mounting motor

2 having shaft 3 driving worm 4 in mesh with worm wheel 5 on shaft 6 provided with sprocket wheel 7 effective through sprocket chain 8 for operating sprocket wheel 9 on shaft 10. This shaft 10 has thereon pulley 55 11 about which extends endless belt or conveyor 12, which, at the remote portion of the frame 1 from this shaft 10, passes about pulley 13 on shaft 14. The conveyor belt 12 is provided with flights 15, 16, 17, 18, 60 19 and 20.

The main frame 1 (Fig. 9) is provided with ledge 20 upon the upper surface of which travels the work supporting conveyor belt 12. This ledge 20 has margin strips 21, 65 22, constituting a way to hold the conveyor belt 12 against lateral shifting, while overhangs 23, 24, preclude jumping of the belt out of this way and allow the upward projection of the series of flights between these 70 overhangs 23, 24, and also the travel of strip upon which the abrading operation is to be performed. The strip, herein shown is a wrought metal bumper for an automobile, having rounded termini 25 which seat between the respective flights 15, 19, while the rest of the flights 16, 17, 18, therebetween sustain the intermediate outwardly projecting portion 26 of the bumper.

Power supply lines 29, 30, extend to starting switch 31 mounted on the frame 1 (Figs. 1, 7) so that when a strip of stock to be operated upon is placed in the machine, the machine may be started by throwing in the switch 31 for causing the motor 2 to effect 85 travel of the stock. Mounted on the frame 1 adjacent the way 20, is a series of brackets (Fig. 5) 32 providing bearings for arms 33 carrying rollers 34. Fixed with the arms 33 upon the opposite sides of the bearings 32 90 are arms 35 from which extend tension springs 36 effective for swinging the rollers 34 toward the work support 12, thereby providing a yieldable device for holding the work in the channel provided therefor on 95 the work support or conveyor 12.

Transversely of the frame 1, rock shafts 37 are provided. These rock shafts have thereon depending lugs 38, providing fulcrum bearings, for carriers or auxiliary 100

frames 39. The carrier 39 is a buffing jack unit mounting affording a rockable platform upon which is disposed motor 40 having shaft 41 provided with pulley 42 from which extends belt 43 about pulley 44 on jack shaft 45 mounted in bearings 46 carried by bracket 47 upstanding from the carrier 39 upon the opposite side of the fulcrum of said carrier from the motor 40. This shaft 45 adjacent the inner bearing 46 is provided with (Fig. 3) pin 48 coaxing in groove 49 like an oscillator or axially shifting drive for this rotating jack shaft 45. The remote portion of this jack shaft 45 is provided with an abrading element 50 detachably mounted thereon by nut 51. This abrading element 50 is disposed above the channel or upper reach of the belt 12.

Each frame or carrier 39, adjacent the motor 40, is provided with supplemental brackets 52, 53. The bracket 52, extending upwardly, is provided with adjusting screw 54 coaxing with stop 55 (Fig. 3) to limit the rocking of the carrier 39 in its inoperative position when the abrading element 50 is thrown upward away from active position, and the motor 40 serves by its weight to hold the device thus rocked. The bracket 53 is provided with set screw 56, which in the reverse rocking of the carrier 39, abuts stop 57 on the frame 1, and thereby limits the downward or operative position of the abrading element 50.

Power lines 29, 30, extend past the switch 31 for starting the conveyor belt motor 2, and have branches 58, 59, therefrom to starting boxes or switches 60 for the respective abrading jacks, thereby providing manually selective control for cutting in the respective motors 40. In practice, this series of jacks along a common reach of the conveyor 12 may have the abrading element 50 for rough grinding, abrading element 61 for finer grinding; and in practice it may be found desirable to have a number of the coarse grinding rolls to be followed by more than one of the fine grinding rolls on account of the amount of material to be taken off, and the character of material being acted upon. Furthermore, in the character of this machine, when these disks wear down, there may be adjustment for the depth of grind or cut on the work by the operation of the screw 56. When this abrading element wears down in use in the adjusted plane or planes. Ready substitution of a new stone or disk thereon may then be had in effecting replacement by the removal of the nut 51. Again, after the stock has been given the rough treatment, the material may be plated or given other type of finish and again sent through the machine for burnishing or buffing operations, to which end, the jack or jacks to the extent desired may be provided with buffing disks on all thereof, or on a desired number thereof,

which buffing disks 62 have a glued disk carrying tripoli or other abrasive, while a succeeding disk 63 may be for the finer polish and charged with rouge.

The carriers 39 are provided, besides the lugs 38, (Figs. 1, 4) with lugs 64, 65, in which are mounted rods 66 having cranks 67. Each rod 66 is provided with an intermediate threaded portion 68 upon which is mounted nut 69 carrying loading means or counterweight 70 below the fulcrum bearings 37, 38, and transversely thereof. Accordingly, by operating the crank 67 there may be effected a traveling of the nut 69 toward or past the shaft 37 in thus determining the degree and direction of the counterweighting of this carrier 39. This affords a nice adjustment for pressing the abrading element on to the work, and is peculiarly advantageous herein for the reason that in the handling of the stock herein disclosed, there is operation of this abrading element in a plurality of planes; the plane of the terminal portions 27; the plane of the intermediate portion 26 upward therefrom; and additionally the approaches 28 therebetween.

In view of the operation of this device beyond different planes, it is desirable for automatic operation that the active elements be prevented from coming in contact with the work support or the flights mounted thereon.

To this end, the bearing 46, adjacent the way 20, carries a supplemental bracket 71 mounted thereon by screw 72. Knurled head screw 73, (Fig. 8) carried by its bracket 71, cooperates with slot 74 in depending bracket 75 for adjusting the position of this bracket 75 carrying roll 76. This roll 76 may be adjusted to be in proximity to portion 77 of the cam riser 78. The idle position of the shaft 45 is determined by the screw 56 abutting stop 57. This riser or cam 78 extends to a flat portion 79, all carried by block 80 having pivot pin 81 movable in slot 82 of plate 83 on the frame 1. This block 80, mounted by the pivot pin 81, has remote therefrom an eye 84 from which extends tension spring 85 to the frame 1 for holding this block 80 in parallelism with the conveyor 12 and against stop 86 mounted on overhang 24. Adjacent the eye 84, the block 80 is provided with pin 87 (Fig. 12) mounting an extension 88 having pivot bearing 89 for trigger 90 normally hanging against the overhang 24, and extending over the belt 12 into the path of flights 16, 17, 18, but clear of the flights 15, 19. When the article of stock in the instance of a strip of material to be treated, is traveling along the channel propelled by this conveyor 12, the inclines 28 guide the trigger 90 so that it rocks on its pivot bearing 89 and is inactive to any operation hereunder.

However, in practice, with the distance between this trigger 90 and pin 91 greater than the distance between the strips of stock on

the way or conveyor 12, this trip action need not occur and to render it inoperative the pin 91 is provided which serves as a guide in the slot 92 of a slide 93, the latter being operable in way 94 of the overhang 24. The slide 93 is supported by the block 80 and carries the pin 91. This slide 93 is shifted transversely of the conveyor 12 by the rounded end of this slide 93 being shoved outward 10 in the slot or guide 94 by an article of stock on the belt 12. This slide 93 swings the block 80 upon its pivot bearing 81 against the tension action of spring 85 and thus serves, when there is stock on the belt 12 to hold the trigger 15 90 clear of the flights on the belt 12.

If the operator should not feed an article of stock on the moving belt 12, the spring 85 would be effective for pulling the block 80 against the stop 86. The slide 93 would 20 not be operable to resist such action and the trigger 90 would be overhanging the way or travel for the flights. The next one of the flights 16, 17, 18, coming along would strike the trigger 90 and shift the block 80 with 25 its pivot pin 81 in the slot 82, thereby causing the cam 78 to ride under the roller 76 so that the roller 76 would approach the way 79 and thus lift the shaft 45 and thereby rock the carrier 39 to such an extent that the abrading 30 element 50, or other element carried by the shaft 45, would be not only clear of the flights and the carrier on the conveyor, but clear of even operating upon work which might project upward therefrom. Thus, the 35 device is automatically shifted into inoperative position. This longitudinal shifting by the travel of the conveyor is to an extent to bring recess 95 (Fig. 12) in the block 80, into registry with plunger 96 mounted in 40 the stop 86 where spring 97 will effect thrusting of this plunger 96 into the recess 95 for holding this block 80 retracted and thus effective for retaining the roller 76 lifted and the abrading element out of operative position. 45 In this shifting of the block 80, trigger 98 pivoted at 99 on the block 80 upon the opposite side from this recess 95, shifts to have cam portion 100 of this trigger 98 ride under adjusting screw 101 carried by overhang 50 102 for rocking this trigger 98 against the resistance of spring 103 (Fig. 10) to have retaining seat 104 of this trigger 98 swing clear of outwardly projecting portion 105 of the extension 88 so that in the further travel of 55 the flight, which has effected the sliding travel of the block 80, the trigger 90 may be swung toward the block 80 and clear of the flight way. This trigger 90 is accordingly thrown out of interfering travel and this 60 device holds the abrading element in operative position where work has not been fed.

When a supply of the material to be acted upon again is given to the machine, and it travels along the channel on the conveyor belt 65 12, there is an automatic resetting of the

abrading device for, (Fig. 12) when the stock rides under roller 106 on the pin 96, the slide 93 is shifted transversely of such belt 12 and rocks the block 80 on its pivot 81 clear of the pin 96 limited in its outward travel by collar 107 riding against flange 108. Thus released from retraction, the spring 85 pulls the block 80 back to have pin 109 strike the projection 105 of the extension 88 rocking such into reset position for the trigger 90 to ride over the stock. While the block 80 is thus retracted, the roller 76 settles down the cam way 78 to above the operative portion 77 thereby allowing the carrier 39 controlled by the counterweight 70 to rock with the shaft 45 in bringing the abrading element into operative position to the supplied work.

Accordingly, herein, there is an automatic safety provision against the abrading wheels attacking the work support in the absence of work, with a control for holding the wheels in operative position at all times when work is fed. There is herein a ready means for shifting any desired number of jacks into or out of operative position with the provision for holding the jacks in operative position and permitting vertical movement to allow for variations in height of the work piece. The oscillator 48, 49, (Fig. 3) gives the wheel a transverse movement in addition to its rotation so that there is avoided any tendency for the abrading element to secure or emphasize imperfections in the stock. The position of the switch 31 is such that in opening thereof, there is simultaneously, a stopping of all of the jacks, and the travel of the conveyor. However, there must be a starting of the conveyor before any jack motor may be operated, and any desired number of jack motors may be operated.

What is claimed and it is desired to secure by United States Letters Patent is:

1. An abrading machine comprising a traveling support for work including flights, an abrading element, and means for throwing the abrading element out of operative position, such means being engaged by a work support which is exposed when work is not being fed through the machine.

2. A frame determining a plane for work, a series of parallel fulcrum bearings approximately in a plane and carried by the frame below said plane of the work, carriers rockably mounted in said fulcrum bearings to swing toward the plane of the work in swinging toward the plane of the axes of the bearings, and an abrading jack and drive therefor mounted on each carrier.

3. A frame determining a plane for work, a series of parallel fulcrum bearings approximately in a plane and carried by the frame below said plane of the work, carriers rockably mounted in said fulcrum bearings to swing toward the plane of the work in swinging toward the plane of

the axes of the bearings, a rotary dressing wheel mounted on each carrier, and driving means for rotating said wheel, the driving means for the respective wheels being clear 5 of axial alignment with the fulcrum bearings for such carrier.

4. A frame determining a plane for work, a series of parallel fulcrum bearings approximately in a plane and carried by the frame 10 below said plane of the work, carriers rockably mounted in said fulcrum bearings to swing toward the plane of the work in swinging toward the plane of the axes of the bearings, a rotary dressing wheel mounted on 15 each carrier, and a drive on each carrier eccentric of the fulcrum bearing mounting for the respective carriers.

5. A frame determining a plane for work, a series of parallel fulcrum bearings approximately in a plane and carried by the frame 20 below said plane of the work, carriers rockably mounted in said fulcrum bearings to swing toward the plane of the work in swinging toward the plane of the axes of the bearings, 25 a rotary dressing wheel mounted on each carrier one way from the fulcrum bearing therefor, and a drive on each carrier disposed on the other side of said bearing from the wheel.

6. A frame determining a plane for work, 30 a series of parallel fulcrum bearings approximately in a plane and carried by the frame below said plane of the work, carriers rockably mounted in said fulcrum bearings to swing toward the plane of the work in swinging 35 toward the plane of the axes of the bearings, and a rotary dressing wheel and drive mounted on each carrier and disposed oppositely as to said bearings in counter-balanced relation.

40 7. A rotary dressing wheel, a horizontal axis rockable mounting therefor, a work carrying support providing a line for work travel and toward and from which support said wheel has a free range of rocking movement 45 toward the horizontal plane of the rocking axis, driving means for progressing the support past the wheel in the plane of the wheel rotation during said rotation, and tangential working path locating loading means adjustable to rock the mounting in either direction 50 in said free range of wheel rocking movement for determining the pressure of the wheel on the work during the shifting of said work when on said support past said wheel.

8. A rotary dressing wheel, a carrier for the wheel, a horizontal axis fulcrum on which said carrier is rockable, said carrier having 60 a guide extending below and both ways past the fulcrum, a drive for the wheel, said drive and wheel being on opposite sides of the fulcrum, and tangential path locating weight below said fulcrum shiftable past the fulcrum along said guide to supplement the

drive weight or to supplement the wheel weight in varying the pressure of the wheel on the tangentially traveling work.

9. A rotary dressing wheel, a carrier, a horizontal axis fulcrum on which said carrier is rockable, a straight line guide, a continuously traveling work support limited to movement along said guide in the plane of the wheel rotation for progressing work past said wheel, a drive for the wheel, said drive and wheel being on opposite sides of the fulcrum, and a frame mounting the fulcrum below the plane of the work on the support to overhang the support toward the direction of the work as approaching the carrier. 70 75 80

10. A rotary dressing wheel, a carrier, a fulcrum on which said carrier is rockable, a straight line guide, a continuously traveling work support limited to movement along 85 said guide in the plane of the wheel rotation for progressing work past said wheel, and tangential working path radial distance locating mechanism comprising an adjustable stop means oppositely extending on the same side of said fulcrum and carried by the carrier, and fixed means as to which the support travels in its tangential path as to the carrier and with which fixed means the adjustable stop means coact for limiting the rocking movement on said fulcrum. 90 95

11. A rotary dressing wheel, a carrier therefor, a straight line guide, a continuously traveling tangential path providing work support limited to movement along said guide in the plane of the wheel rotation for progressing work past and below said wheel, a fulcrum for the carrier below said support on which the wheel may rock from the fulcrum toward the approaching work on the support, and a drive on the carrier on the opposite side of the fulcrum from the wheel for rotating the wheel. 100 105

12. A support for positioning work, a rotary dressing wheel for the work, a wheel mounting permitting the rotating wheel freely to find its center, a fulcrum for the mounting below said support, a drive on the mounting on the opposite side of the fulcrum from the wheel for rotating the wheel, and a counterweight below said fulcrum adjustable from one side past said fulcrum to the other side for thereby varying the work disturbance of the wheel free position for rotation. 110 115

13. A rotary dressing wheel, a carrier therefor, a straight line guide, a continuously traveling work support limited to movement along said guide in the plane of the wheel rotation for progressing work past said wheel, a fulcrum for the carrier located below the working position of the wheel, a drive on the carrier for the wheel and disposed laterally of the fulcrum oppositely from the wheel, and an oscillator on the carrier for effecting transverse reciprocation between the work on the support and said wheel. 120 125 130

14. A rotary dressing wheel, a carrier therefor, a straight line guide, a continuously traveling work support limited to movement along said guide in the plane of the 5 wheel rotation for progressing work past said wheel, a horizontal axis fulcrum for the carrier located below the work coating position of the wheel, a drive on the carrier for the wheel and disposed laterally of the fulcrum and opposite from the wheel, and an oscillator on the carrier for the wheel for effecting transverse reciprocation of the rotating wheel as to the work on the support.

15. A rotary dressing wheel, a relatively 15 traveling work support, said wheel movable in operation for acting on said support but for the intervening work, and a work position-effecting control movable relatively to the work supporting wheel for rendering said 20 wheel ineffective for acting on the support as the support is clear of the work.

16. A rotary dressing wheel, a relatively traveling work support, said wheel movable in operation for acting on said support but 25 for the intervening work, and an automatic cut-in movable relatively to the work supporting wheel for the wheel for rendering said wheel effective for acting on work on the support as the support is charged with 30 work.

17. Work dressing equipment comprising an endless conveyor, work engaging flights on said conveyor, a drive for the conveyor, a plurality of independent rockably mounted 35 rotary dressing wheels movable radially into position for coating with work on said conveyor in sequence, an independent drive for each wheel, a common mounting for the wheel and drive as a unit, a pivot bearing for the 40 mounting directing the wheel toward the approaching direction of the flights of the conveyor, and a stop device effective for shutting down the conveyor and wheel drives.

18. A work dressing machine comprising 45 an endless conveyor, a frame therefor, a conveyor drive carried by the frame, dressing wheels disposed along said conveyor, independent carriers for said wheels pivotally mounted on said frame and overhanging the 50 conveyor toward the direction of conveyor travel, a wheel actuating motor on each carrier, means on the conveyor positioning work for said wheels, and loading means determining the pressure on said wheels toward said 55 work.

19. Work dressing equipment comprising an endless conveyor, work engaging flights on said conveyor, a motor for driving the conveyor, a main support, a series of auxiliary 60 supports independently rockably mounted on the main support, a rotary dressing wheel on each auxiliary support movable radially into position for coating with work on said conveyor in sequence, an independent motor 65 on each auxiliary support for each wheel and

rockable therewith as a unit, and independent cut-in switches for the separate motors and the conveyor drive.

20. Work dressing equipment comprising an endless conveyor, work engaging flights on 70 said conveyor, a drive for the conveyor, a main support, a series of independently rockable auxiliary supports on the main support, rotary dressing wheels on said respective auxiliary supports movable radially into position for coating with work on said conveyor in sequence, an independent motor on each auxiliary support for rocking therewith, transmission connections between the motors and wheels, and means permitting rocking 75 of the wheels independently clear of working position and independently of stopping the wheels.

21. A work dressing machine comprising an endless conveyor, a main support there- 80 for, a conveyor drive carried by the support, a series of dressing wheels disposed along said conveyor, independent auxiliary supports for said wheels, horizontal axis-pro- 85 viding bearings pivotally mounting said re- spective auxiliary supports on said main sup- port locating the wheels for overhanging the conveyor, a wheel actuating motor on each auxiliary support oppositely of its bearing 90 from the wheel, and means on the conveyor 95 positioning work for said wheels.

22. An abrading machine comprising a traveling support for work, a rotatable abrading element, a shiftable control coating in 100 the zone of work progress of the traveling support independently of the position of the abrading element and automatically movable when the support region is clear of the work for rendering said element ineffective for act- 105 ing on said work at any position of the ele- ment, and resetting means coating with the work on the support for acting on said con- trol for allowing the abrading element to move into working position to act on said work.

In witness whereof I affix my signature.
WILLIAM C. GROB.
